(57) **CLAIM**

The ornamental design for a multi-level display hook, as shown and described.

DESCRIPTION

FIG. 1 is a top front perspective view;
FIG. 2 is a front side elevational view thereof;
FIG. 3 is a right side elevational view thereof;
FIG. 4 is a left side elevational view thereof;
FIG. 5 is a bottom plan view thereof;
FIG. 6 is a top plan view thereof; and,
FIG. 7 is a back side elevational view thereof.

The broken lines immediately adjacent the shaded areas represent the bounds of the claim and all other broken lines are for illustrative purposes only. None of the broken lines form a part of the claimed design.

1 Claim, 3 Drawing Sheets

FIG. 3.

FIG. 4.

FIG. 5.

FIG. 7.
